ROLLING DOOR STRUCTURE

William M. Brumst, Columbus, Ohio, assignor to
General Door Company, Reno, Nevada, a cor-
poration of Nevada

Application January 8, 1936, Serial No. 58,137

8 Claims. (Cl. 189—56)

This invention relates to rolling door structures and particularly to doors having curtains adapted to be rolled up on drums or similar apparatus.

5 One object of this invention is to provide a rolling door having a curtain consisting of a reticulated structure, the members of which are hinged relatively to one another so as to be capable of being rolled up on a drum or similar member and unrolled to close the door.

10 Another object is to provide a rolling door having a curtain consisting of a plurality of rod-like members interconnected by lattice members and hinged relatively to one another so as to form 15 a reticulated curtain.

15 Another object of this invention is to provide a curtain for a rolling door, consisting of a series of short shouldered rods interconnected horizontally by bars forming a diamond-shaped structure, the upper and lower ends of which are pivoted upon rods running the entire width of the 20 door.

In the drawings:

Figure 1 is a front elevation, partly in section, 25 of the rolling door of my invention, showing the door in its lowered position;

Figure 2 is an enlarged vertical section through the door of Figure 1, taken along the line 2—2 thereof;

30 Figure 3 is an enlarged detail view of a portion of the curtain;

Figure 4 is a section along the line 4—4 of Figure 3;

35 Figure 5 is a section along the line 5—5 of Figure 1, showing the edge of the curtain and the guiding member therefor.

Referring to the drawings in detail, Figures 1 and 5 show a wall 10 having an opening 11 for the reception of a door. Secured to the wall on each side of the door opening 11 is an angle member 12, as by the bolts 13. To each angle member 12 is secured a channel member 14 with the opening thereof facing inwardly. The opening is partly closed by flanges 15. These flanges 40 serve the purpose of retaining the sides of the curtain in lateral alignment, and yet permit the curtain itself to pass between them. To the wall above the opening 11 are secured frame members 16, as by the bolts 17. (See, for instance, Figure 1). These frame members serve to support the shaft 18 and the rotatable drum 19, upon which, the curtain hereinafter described is rolled when the door is opened. Any suitable means 45 may be provided for rotating the drum 19 in order to wind up or lower the curtain. These

mechanisms are well known to those skilled in the art and form no part of the present invention.

Also arranged above the door opening 11 and positioned to conceal and protect the mechanism 5 is a hood 20. This hood encloses the drum 19 and the adjacent working parts.

Secured to the drum 19, as by the rivets 21, are links 22, by which the curtain, generally designated 23, is secured to the drum 19. The curtain 23 consists of a plurality of side plates 24, the upper ends of which are offset, as at 25, to permit the adjacent side members 24 to be placed in alignment with one another. The extremities of each side plate 24 are bored, as at 26 and 27, 10 to receive hinge rods 28 passing therethrough and serving to tie the side plates 24 together. Pins 28' serve to retain the side plates 24 upon the hinge rods 28. The lowermost hinge rod 28 is provided with a straight side plate 29, secured 15 as by welding to the bottom member 30 of the door.

The bottom member 30 is preferably of T-shaped cross section (Figure 4) and is provided with angled members 31 secured thereto and 20 serving as handles for assistance in raising the door manually. Secured at intervals along the bottom member 30 are links 32, whose upper ends 25 are provided with bores 33 encircling the lowermost hinge rod 28. The mid-portion of each side plate 24 is provided with a hole 34 which 30 serves to receive the end of short end rods 35, the opposite ends of which are secured in similar holes 36 in a lattice or connecting member, generally designated 37, having a central portion 38, 35 angled intermediate portions 39 and end portions 40 and 41, which are substantially parallel to the middle portion 38. The opposite ends of the short end rods 35 are secured to their respective members 24 and 37 by any suitable means, the 40 means shown being that of offsetting the ends to form an enlarged portion similar to the head of the rivet.

It will be seen that the ends of the short rods 35 are slightly reduced in diameter at the points 45 where they pass through the holes 34 and 36, the annular shoulders formed thereby serving as abutments to position the end rod 35 between the side member 24 and the lattice member 37. Arranged in alignment with the end rods 35 are 50 other short rods 42 serving as tie members and secured at their ends to similar lattice members 37. The adjacent lattice members 37 face one another so as to form a roughly diamond-shaped aperture therebetween. The lower end portions 55

40 of the lattice members 37 are bored, as at 43, to receive the hinge rod 28, and are arranged on opposite sides of each link 32, the latter being bored, as at 44, to receive the hinge rod 5 28. The upper ends 41 of the lattice members 37 are similarly bored, as at 45, and are positioned to engage one another face to face, the adjacent lower ends 40 of the lattice members 37 thereabove being placed on the outer sides 10 thereof (Figure 3). Thus the upper ends 41 of each lattice member 37 serve as spacing members for the lower ends 40 of the lattice members immediately above. Also the various rods 15 35 and 42, in conjunction with the lattice members 37 and the hinge rods 28, form a reticulated curtain having hinged side plates 24 on each vertical edge thereof. The rods 42 and 35 with their lattice members 37 form rigid units extending from one side of the curtain to the other, 20 each rigid unit being hinged above and below its rods 42 and 35. The vertical edges of the curtain slide in the channel member 14 and are prevented from withdrawal by the flanges 15 thereof.

25 In the operation of the rolling door structure of this invention, assuming the parts to be in the closed position shown in Figure 1, the door is opened by causing the drum 19 to be rotated by suitable power mechanism. This mechanism 30 may be operated either by power or manually in ways well known to those skilled in the art. As the drum 19 rotates, the links 22, secured thereto, travel circumferentially around the shaft 18, and the side plates 24, which are connected 35 to the links 22 and to each other, are wound up on the rotating drum 19 in the manner shown in Figure 2.

Each horizontal unit composed of the rods 35 and 42 and the lattice members 37 hinges at its 40 upper and lower extremities on the hinge rods 28 and is deposited upon the periphery of the rotating drum 19 as it reaches that location.

As the curtain is wound up on the drum, the bottom member 30 passes the top 46 of the 45 opening 11 and enters the aperture 41 between the lower edge of the member 48 supporting the hood 20 and the opposing lower edge of the member 49, the latter being secured to the wall 10 by the bolts 50. When the door is in its topmost 50 position, the bottom edge of the bottom member 30 closes the aperture 41. To unwind the door and close the opening, the foregoing operations are reversed, the drum 19 is rotated in a counter-clockwise direction and the various side members 55 24 disengage themselves from the periphery of the drum 19. The side members 24 and hinge rods 28 pass downwardly within the channel member 14 until the bottom member 30 rests upon the ground or door sill, thus closing the 60 opening.

It will be understood that I desire to comprehend within my invention such modifications as come within the scope of the claims and the invention.

65 Having thus fully described my invention, what I claim as new and desire to secure by Letters Patent is:

1. A rolling door structure comprising a frame, a curtain-receiving member adapted to engage 70 said frame, and a reticulated curtain supported by said curtain-receiving member, said reticulated member having a plurality of spaced hinge members extending between the opposite sides of said curtain, a plurality of connecting members pivot- 75 ally connected to said hinge members and a plu-

rality of tie rods spacedly engaging said connecting members, said connecting members being secured to the ends of said tie rods at points intermediate the pivotal connections of said connecting members with said hinge members, certain pairs 5 of said connecting members consisting of angled strips bent oppositely to form a lattice unit, said lattice units forming a reticulated structure with said tie rods and said hinge members.

2. A rolling door curtain comprising a plurality 10 of spaced hinge members extending between the opposite sides of said curtain, a plurality of connecting members hingedly arranged therebetween, and a plurality of tie members having their opposite ends secured to said connecting members, said connecting members having their opposite ends pivotally secured to said hinge members, certain of the horizontally adjacent connecting members being bent oppositely to form lattice 15 units.

3. A rolling door curtain comprising a plurality 20 of spaced hinge members extending between the opposite sides of said curtain, a plurality of connecting members hingedly arranged therebetween, and a plurality of tie members having their opposite ends secured to said connecting members, said connecting members having their opposite ends pivotally secured to said hinge members, certain of the horizontally adjacent connecting members being bent oppositely to form a 25 lattice unit, the vertically adjacent ends of said connecting members being arranged in face-to-face engagement with one another.

4. A rolling door curtain comprising a plurality 30 of spaced hinge members extending between the opposite sides of said curtain, a plurality of connecting members hingedly arranged therebetween, and a plurality of tie members having their opposite ends secured to said connecting members, said connecting members having their opposite ends pivotally secured to said hinge members, certain of the horizontally adjacent connecting members being bent oppositely to form a 35 lattice unit, the vertically adjacent ends of said connecting members being arranged in face-to-face engagement with one another, the abutting ends 40 of one associated pair of connecting members being arranged to space the adjacent ends of the associated connecting members in immediate 45 proximity thereto.

5. A rolling door curtain comprising a plurality 50 of spaced hinge members extending between the opposite sides of said curtain, a plurality of connecting members hingedly arranged therebetween, and a plurality of tie members having their opposite ends secured to said connecting members, said connecting members having their opposite ends pivotally secured to said hinge members, certain of the horizontally adjacent connecting members being bent oppositely to form a 55 lattice unit, the vertically adjacent ends of said connecting members being arranged in face-to-face engagement with one another, the abutting ends 60 of one associated pair of connecting members being arranged to space the adjacent ends of the associated connecting members in immediate 65 proximity thereto, the opposite ends of said first-mentioned associated pair of connecting members being arranged in spaced relationship with the ends of the associated connecting members 70 directly opposite said second-mentioned connecting members held therebetween.

6. A rolling door curtain comprising a plurality 75 of hinge members extending from side to side of said curtain, a plurality of side connecting mem-

bers pivotally engaging the ends of said hinge members, a plurality of lattice members pivotally interconnecting said hinge members at points intermediate the ends thereof, and a plurality of tie members extending between adjacent lattice members and having their opposite ends terminating in the adjacent sides of said lattice members.

7. A rolling door curtain comprising a plurality of hinge members extending from side to side of said curtain, a plurality of side connecting members pivotally engaging the ends of said hinge members, a plurality of lattice members pivotally interconnecting said hinge members at points intermediate the ends thereof, and a plurality of tie members arranged between adjacent lattice members and having their opposite ends terminating in the adjacent sides of said lattice members, cer-

tain pairs of said lattice members being bent oppositely to form apertures therebetween and adapted to provide a reticulated structure in assembly.

8. A rolling door curtain comprising a plurality of hinge members extending from side to side of said curtain, a plurality of side connecting members pivotally engaging the ends of said hinge members, a plurality of lattice members pivotally interconnecting said hinge members at points intermediate the ends thereof, and a plurality of tie members arranged between adjacent lattice members, one end of each side connecting member being offset to receive the adjacent side connecting member in alignment therewith.

WILLIAM M. BRUNST.
